UNITED STATES PATENT OFFICE.

CHARLES C. BADEAU, OF BETHLEHEM, PENNSYLVANIA, ASSIGNOR TO ROLLER-SMITH COMPANY, A CORPORATION OF NEW YORK.

TIME-LIMIT CIRCUIT-BREAKER.

1,124,832.

Specification of Letters Patent. Patented Jan. 12, 1915.

Application filed August 12, 1908. Serial No. 449,021.

To all whom it may concern:

Be it known that I, CHARLES C. BADEAU, a citizen of the United States, residing at Bethlehem, in the county of Northampton and State of Pennsylvania, have invented certain new and useful Improvements in Time-Limit Circuit-Breakers, of which the following is a full, clear, and exact specification.

10 My invention relates to time limit circuit breakers, and particularly of the inverse time element type operating in a certain definite time upon a definite overload, but which operates in a greater or less length of time depending upon the amount of the overload current.

15 By my invention I secure a time limit circuit breaker, which is simple in form of construction, compact and reliable; also one in which the duration of the overload will be allowed to continue a length of time dependent upon the amount of overload current and which upon a very large overload will operate without any appreciable 20 interval of time.

25 Other advantages and objects of my invention will be understood from the following description and accompanying drawings, in which—

30 Figure 1 is a diagram illustrating the principle of one form of my invention; Fig. 2 is a side view of one form of circuit breaker embodying my invention; Fig. 3 is a front elevation thereof; and Fig. 4 is a vertical cross section.

35 Referring to Fig. 1, there are shown two coils 1, 2 connected in series with each other and with the circuit to be controlled. The upper overload coil 1 is shown as having 40 a movable core 3 adapted to be raised and operate the releasing means of the circuit breaker either mechanically as is customary or electrically by the closing or opening of a circuit, and in Fig. 1, I have indicated the core 3 as carrying a circuit closer 4 which when the core is raised will engage the fixed contacts 5 and close a circuit for controlling the opening of the circuit breaker. The lower overload coil 2 is shown 45 as having a movable core 6 and carries an upper extension 7 adapted to mechanically engage the lower end of core 3. The core 6 is damped in its movement by any suitable means such as dash-pot 8, which allows slow upward movement of core 6 and a

rapid downward movement. The core 8 of the upper overload coil is not damped in its movement.

The undamped armature is normally so far removed from the influence of the pull 50 of the overload coil 1, that a normal overload will not raise its core nor cause the circuit breaker to be opened, but with a very excessive overload, even though continuing momentarily, the core 3 will be 55 quickly raised by the influence of its coil and thus promptly open the circuit breaker. With normal overloads however, the coil 2 having the damped core or armature serves as the initial controlling part and upon any 60 overload the core 6 will gradually move upward and also cause the core 3 of the upper overload coil to also gradually move upward. If the overload is comparatively 65 small and continues only a short length of time, the two cores will fall to their lower positions and not operate the circuit breaker. If, however, the overload continues a sufficient length of time, the raising of the undamped core 3 by the damped core 6 70 will result in bringing the core 3 sufficiently within the influence of its coil 1 so that the latter will act upon the core 3 and quickly raise the same and open the circuit breaker. It will be evident that the circuit 75 breaker will be opened within a time interval depending upon the amount of the overload current because the coil 1 will operate to raise its core from the extension of the core 6 quicker if a large overload occurs 80 than when a small overload occurs. Also, with a large overload the damped core will be required to raise the undamped core a shorter distance within the coil 1 to cause the opening of the circuit breaker than when 85 a smaller overload occurs, and the more the overload the less is the distance which the undamped armature must be moved. Consequently, a less time interval is required 90 for opening the circuit breaker with a heavy 100 overload than is the case with a small overload. It will also be seen that the damped core does not need to have much power as it does not trip the circuit breaker but merely places the undamped core in such 105 a position that it will trip the circuit breaker. It will also be seen as above mentioned that the undamped core will respond immediately to a heavy short circuit and instantly open the circuit breaker and thus 110

avoids the lapse of any time interval under such conditions.

It may sometimes be desirable to use two independent armatures each working on its own magnetic circuit and energized by coils electrically connected in series as above described, or the two armatures may sometimes be operated magnetically in multiple on a circuit energized by one coil as hereinafter described. If two coils be used they may be in separate circuits such as in controlling a motor generator set where it is sometimes advisable to have an overload on one coil to open or close the circuit of the other coil.

Referring to the structure shown in Figs. 2, 3 and 4, the supporting board is indicated at 10 to which is fixed a lower terminal 11 and an upper terminal 12 of the circuit breaker. Two supporting side frames 13, 13', are indicated, and pivotally mounted between the side frames 13, 13' is a magnet core 14 to which is connected in the present form of construction the inner end of the overload coil 15 in the form of a ribbon and coiled to form a spring, the outer end of which is fixed and connected to terminal 11. Fixed to the core 14 are conducting arms 16 which carry suitable contacts at their upper end for engaging with the yieldable brush contacts 17 which are electrically connected to the upper terminal 12. The spring tension of the overload coil 15 tends to normally force the circuit breaker arms 16 to open position from the fixed contacts 17.

Pivoted to the side supports at 18 is a handle 20, the supporting frame of which carries a roller 21 adapted to engage with a roller 22 supported between the side arms 16. When the circuit breaker arm is open, the same may be closed by moving the handle 20 downward which will cause the roller 21 to close the circuit breaker by engagement with the roller 22 and will then hold the circuit breaker in closed position by reason of the axis of the roller 21 being in or slightly above the plane through the axes of roller 22 and the pivotal support of the handle, the pin 18' serving to limit the movement of roller 21. This support is provided with a lower extension 23.

Pivotedly mounted at 24 on the side supports 13, 13' is a U-shaped undamped armature having a central portion 25 and two downwardly extending arms 26. This U-shaped armature is adapted to be acted upon by the overload coil 15 and its iron core 14, and upon the occurrence of a heavy short circuit, the arms 26 will be attracted by the core 14 and trip the circuit breaker by the engagement of an extension 27 from the armature which engages the extension 23 and so causes the roller 21 to be moved downward and permit the opening of the circuit breaker.

The damped armature is shown as having

a central support 28 pivotally supported upon a rod 29 and carrying a U-shaped armature having the central portion 30 and arms 31 which extend outside of the arms 26 of the undamped armature. Within the arms 31 and supported therefrom are rollers 32 each adapted to engage the lower portions of the arms 26 respectively. Magnetically united with the core 14 of the overload coil are iron poles 33 which latter are located respectively on the outside of the side frames 13, 13' and serve as the poles for the attraction of the arms 31 of the damped armature. The poles 33 and arms 31 are so shaped with reference to each other as to form what is known as a constant pull magnet, the force exerted tending to rotate the damped armature about its pivot, and being substantially constant in any position. It will be seen that the undamped and damped armatures are in magnetic multiple relation to the core of the overload coil, the magnetic circuit from one pole of the core 14 to the other being completed through the U-shaped undamped armature by crossing the two air gaps between the ends of the core 14 to the arms of the undamped armature within the side frames 13, 13' and the magnetic circuit of the damped armature being completed from the outer poles 33 of the core 14 through the U-shaped damped armature across the two air spaces between the poles 33 and the arms 31 on the outside of the side frames.

Any suitable means may be provided for adjusting the normal position of the undamped armature and thereby determine the strength of overload current which will attract it from said position, and similarly any suitable adjustable means may be provided for the damped armature, the form indicated in the present structure being an adjustable weight 34 adapted to be adjusted upon the support 28.

The damping means for the damped armature may of course be of any suitable form, but in the present instance I have devised an electric damping means comprising a disk 35 of conducting material fixed to the shaft 29. The sides of this disk are embraced by the poles of a permanent magnet 36 fixed to the side frame 13' by a screw 37 about which the magnet may be angularly adjusted and clamped in any desired position by the screw 38 which projects through the slot 39 in the side frame and into the magnet 36. It will be seen that by shifting the position of the clamping screw 38 in the slot 39, the poles of the magnet 36 will be adjusted with relation to the disk 35 and thereby determine the damping or braking action upon the disk and consequently the rate of movement thereof. Fixed upon the staff 29 which drives the retarding disks 35 is a spur gear 40 which 130

meshes with a larger gear 41 mounted on a shaft extending between the side frames 13, 13'. The shaft carrying the gear 41 also carries a spur gear 42 which in turn meshes with a larger gear 43 which latter is freely movable upon a sleeve 44 upon the shaft 29. The periphery of the gear 43 is engaged by a latch 45 pivotally mounted upon an arm 46 fixed to the sleeve 44. The latch is adapted to normally engage the gear 43 and move the same when forced downward and ride over the teeth of the gear in its upward movement, the upward movement being limited by a pin 47 engaging a projection 48 on the side frame 13. The support 28 for the damped armature is fixed to a sleeve 49 freely movable upon the shaft 29 and is provided with jaws adapted to engage similar jaws from the sleeve 44 forming a jaw clutch 50. A space is provided between the jaws of the two sleeves 44 and 49 so as to allow a slight movement of the damped armature before operating the damping means and thus impart a blow to the damping means to overcome the inertia and friction of the gearing and thus more easily set the same in motion. It will be understood that when the damped armature is raised by overload and begins to approach the poles 33 of the overload coil, the damped armature will also raise the undamped armature mechanically and by the medium of the jaw clutch, the train of gears will be set in motion, giving a comparatively high speed to the driven disk 35, which by the production of eddy currents will tend to retard the upward movement of the damped armature. As soon as the damped armature has raised the undamped armature to such position that it will be raised by the magnetic effect of the overload coil, the undamped armature will suddenly leave the damped armature and quickly open the circuit breaker as above described. When the overload ceases to exist or in case it does not continue a sufficient length of time, both armatures will fall to their normal positions and the latch 45 will pass over the teeth of the gear wheel 43 without actuating the same and assume the normal position shown in the drawings.

It will be understood that my invention may be embodied in various other forms of apparatus and various modifications may be made therein without departing from the scope of my invention.

Having thus described my invention, I declare that what I claim as new and desire to secure by Letters Patent, is,—

1. An automatic circuit breaker comprising a coil, a support therefor, an element actuated by said coil upon excessive overload current for controlling the opening of the circuit breaker, a second element actuated by said coil upon moderate overload

current, means for mounting said elements on said support so that under normal current said first-named element is spaced a certain distance from said coil and under moderate overload current conditions is moved by said second element into closer proximity to said coil, and means for damping the movement of said second element.

2. An automatic circuit breaker comprising a coil, two co-acting movable elements controlled by said coil, the movement of one of said elements being damped and the other undamped, the former controlling the movement of the undamped element under moderate overload, and mechanical means controlled directly thereby for tripping the circuit breaker.

3. An automatic circuit breaker comprising two movable elements, a coil controlling the movement of both of said elements, one of said elements being damped and responding to moderate overload conditions, and the other of said elements being undamped and responding quickly to excessive overload, a support for said coil, means for independently mounting said elements on said support, said undamped element being related to said damped element so that the distance between said coil and said undamped element is progressively decreased by the action of said damped element upon progressive increase of overload, and means controlled by said elements for opening the circuit breaker.

4. An automatic circuit breaker comprising two movable elements, a coil controlling the movement of both of said elements, one of said elements being damped and responding to moderate overload upon expiration of a predetermined time interval and controlling the movement of the other of said elements under conditions of moderate overload, the latter element being undamped, and mechanical means controlled directly by said elements for tripping the circuit breaker.

5. An automatic circuit breaker comprising means for creating a magnetic field, a magnetic movable element controlled thereby, a second magnetic movable element controlled by said means and mechanically regulating the distance between said means and said first-named element in accordance with the degree of overload, and means for damping the movement of said second element.

6. An automatic circuit breaker comprising an overload coil for creating a magnetic field, a tripping element controlled by said field, a second movable element controlled by said field and controlling the movement of the first named element and mounted independently of said first-named element, and means for damping the movement of said second element.

7. An automatic circuit breaker comprising an overload coil for creating a magnetic field, a tripping element controlled by said field, a second movable element controlled by said field and controlling the movement of the first named element and mounted independently of said first-named element, and inverse time element means for damping the movement of said second element.
- 10 8. An automatic circuit breaker comprising an overload coil for creating a magnetic field, a tripping element controlled by said field, a second movable element controlled by said field and controlling the movement of the first named element and mounted independently of said first-named element, inverse time element damping means, and means for driving said means by said second element.
- 15 9. An automatic circuit breaker comprising an overload coil for creating a magnetic field, a tripping element controlled by said field, a pivotally mounted movable element controlled by said field and controlling the movement of said first named element and mounted independently of said first-named element, inverse time element damping means, and a lost motion device for driving said means by said pivotally mounted element.
- 20 10. An automatic circuit breaker comprising a controlling coil, an element actuated thereby upon excessive overload current for controlling the opening of the circuit breaker, a second element actuated by said coil upon moderate overload current and mounted independently of said first-named element and causing the movement of the first-named element, and means for retarding the movement of said second element.
- 25 11. An automatic circuit breaker comprising a coil, an element for controlling the opening of the circuit breaker controlled by said coil, a second movable element controlled by said coil and adapted to move said first-named element, said first-named element being free to move independently of the movement of said second element, and means for damping the movement of said second element.
- 30 12. An automatic circuit breaker comprising a coil, two co-acting movable elements controlled by said coil, the movement of one of said elements being damped, said damped element controlling the movement of the other element so that said other element is moved into closer proximity to said coil
- 35 upon increase of overload, and means controlled directly by at least one of said elements for opening the circuit breaker.
- 40 13. An automatic circuit breaker comprising a breaking mechanism for opening the circuit breaker, a coil, two movable elements adapted to be actuated by said coil, one of said elements controlling the relation of the other of said elements with respect to said coil, mechanical means adapted to be actuated by one of said elements for operating said breaking mechanism, said last named movable element being related to said mechanical means to allow of accelerated movement before actuating said mechanical means, and means for damping the movement of one of said movable elements.
- 45 14. An automatic circuit breaker comprising a coil, a breaking mechanism for opening the circuit, and a momentum means for causing the operation of said breaking mechanism, said means including a plurality of movable elements adapted to be actuated by said coil, certain of said elements varying the relation of the remainder of said elements with respect to said coil according to the magnitude and duration of overload conditions.
- 50 15. An automatic circuit breaker comprising a coil, a breaking mechanism for opening the circuit breaker, two movable elements adapted to be actuated by said coil, one of said elements being damped and responding to moderate overload, the other of said elements being undamped and responding to excessive overload, said damped element being constructed to regulate the relation of said undamped element with respect to said coil, and means directly controlled by said undamped element for releasing said breaking mechanism.
- 55 16. An automatic circuit breaker comprising in combination a coil, a breaking mechanism for opening the circuit breaker, a magnetic element adapted to cause the release of said breaking mechanism, a second magnetic element adapted to control the position of said first-named magnetic element with relation to said coil under certain conditions, said two magnetic elements being in magnetic multiple relation to said coil.

In testimony whereof I affix my signature, in presence of two witnesses.
